GOLF GAME

George J. Forcier, Cleveland, Ohio

Application April 1, 1936, Serial No. 72,038

5 Claims. (Cl. 273—35)

This invention relates to an improvement in simulated golf games, which may be set up for use either inside or outside and is designed for use with the regulation clubs and balls to afford amusement and to increase the efficiency and skill through practice, of the players.

One object is to provide a game whereby both driving and putting is employed, and which provides hazards and scoring similar to the actual game of golf.

Another object is to provide a means in the structure whereby the balls will return through channels to the player.

A further object is to provide a structure of sufficient sturdiness to permit hard drives without overturning and of such size as proves adequate for both indoor and outdoor use; being constructed of assembled parts to facilitate packing, shipping and assembling.

These and other objects may be noted from the following specification and its accompanying illustrations, in which:—

Figure 1 is a front elevation of the device with the center section out.

Fig. 2 is a section on line 2—2 of Fig. 1.

Fig. 3 is a side elevation with the center section out.

Fig. 4 is a section on line 4—4 of Fig. 2.

Fig. 5 is a section on line 5—5 of Fig. 2.

Fig. 6 is an enlarged section on line 6—6 of Fig. 2.

Fig. 7 is a perspective of a fragment of the scoring and return channels and the hole in one.

Fig. 8 is a top plan view of the net bar support.

Fig. 9 is a side elevation of Fig. 8.

Referring to the drawings: a frame consists of a series of standards consisting of heavy bases 10, 11, 12, 13 and 14 substantially as shown, and

40 having angular upright bars 15, 16, 17, 18 and 19 screwed therein, and a pair of semi-circular rods 20 and 20a (which may be of either the telescopic or sectional type to facilitate shipping and assembling) attached thereto by means of

45 bracket clamps 21 and 21a superimposed over said bars 15, 16, 17, 18 and 19 and projecting inwardly therefrom, the lower series of bracket clamps being slidably supported thereon, while the upper bracket clamps 21a are rigidly attached

50 to said bars 15, 16, 17, 18 and 19.

The connection clamps 21 and 21a have a split eye 22 at one end, the short projecting split end 22a having a slot 23 therethrough substantially as shown in Fig. 9; the opposed end of the connection clamp terminating in a round boss 24

with an aperture 25 through the center thereof and a threaded recess 26 in the top surface for a set screw 27.

A pair of bolts 28 and 29 secure the bracket clamps 21 slidably upon the bars 15, 16, 17, 18 and 19, above and adjacent to the bases 10, 11, 12, 13 and 14, the bolts being mounted through apertures 30 and 31 in the connection clamp 21 and projecting through the slot 23 in the short end are secured by lock washers 32 and nuts 33.

The connection clamps 21a are secured rigidly to the bars 15, 16, 17, 18 and 19 at or adjacent to the top ends of said rods in the same manner and by the same means.

The rods 20 and 20a are mounted through the apertures 25 in the connection clamps 21 and 21a and secured thereto by set screws 27.

A base frame 34 (made of wire mesh, or a moulded or case light-weight alloy or any material having body but little weight) has a series 20 of channels or grooves 35, 36, 37, 38, 39 and 40 semicircular in contour and running parallel to each other with a common center. A slight incline is shown at 41a in the top surface 41 of the frame 34, adjacent to and forward of the channel 40, the inclination being toward the common center.

A pair of depressions 42 and 43 in the frame 34 span an area of the channels 35 and 36 of approximately 30 degrees to 60 degrees on an angle from the center line of the device.

An orifice 44 is in the exact center of the channel 39 on a line from the common center; a block 45 substantially of the shape shown in Figs. 1, 2 and 5, has a tee 46, preferably of rubber or the like, adapted to be pressed into a depression 47 in the center of said block and projecting slightly above the top surface.

A pair of apertures 48 and 49 in the frame 34 and on opposed sides of said frame substantially as shown in Fig. 2 are directly in line vertically with the lower forwardly curved brackets 50 rigidly secured to the rod 20 by set screws 51 forward of and adjacent to the connection clamps 21 attached to the bars 16 and 18 in the bases 11 and 13.

A pair of similar brackets 52 are mounted in the same manner and by the same means on the upper rod 20a.

A frame cover 53, of canvas, net or the like, is secured to the frame 34 by suitable means, depending upon the material used in manufacturing the said frame, this cover 53 having the same contour as the frame, including the channels, apertures, depressions and the like, speci-

fied in the above description pertaining to the frame structure. The cover 53 is attached by suitable means, such as curtain hooks or the like sewed around the outer contour of the frame 5 cover, to the rings 54 superimposed over the rod 20 and being evenly spaced at intervals around the circumference of said rod 20.

End drops or curtains 55 and 56 of the same material as the cover 53, are attached at their 10 top edge to rings 57 on the upper rod 20a in substantially the same manner as hereinabove described, these drops 55 and 56 being secured loosely in a vertical plane between the upright bars 15 and 16 and 18 and 19; the bottom edge of 15 said drops being secured to the rings 54, the inner vertical edge of said drops 55 and 56 being attached to the forwardly curved brackets 50 and 52 secured at the top to the rod 20a and to the rod 20 at the bottom.

20 Center drops 58 and 59 are secured at their top edges to said rings 57 on the upper rod 20a between the uprights 16 and 17 and 17 and 18 and at their bottom edge to rings 54 on the lower rod 20; said drops being stretched between said 25 rods 20 and 20a; weights 60 being provided and secured to said rods, to ensure the constant tension on the center drops 58 and 59.

A semicircular top cover 61 of the same material as the drops, spans the area between the 30 tops of the upright bars 15, 16, 17 and 18 and is drawn taut, the edges of the semicircular top cover being secured to the rings 57 on the rod 20a.

The center drops 58 and 59 have vertical bands 35 or lines 62 and 63 down the center thereof from top to bottom, those portions on each side of the bar 17 being the fairway, the outer portion of center drops 58 being the bunkers and the outer portion of center drops 59 being the sand trap. The end drops 55 and 56 are the rough.

40 The semicircular channels 35 to 40 inclusive are used to score points, the outer channel 35 counting the least and the inner channels 39 and 40 counting the most, the ball 62 being returned to the player through the channel into which it 45 drops, the depressions 42 and 43 being used as traps to reduce the score when the ball 62 drops therein and rolls into the channels 35 or 36. The channel 40 has its outlet through the channel 39 as shown in Fig. 2.

50 The orifice 44 in the center of the channel 39 is utilized as a hole in one when the ball 62 is driven from the tee 46 of the block 45, against the vertical drops and falls into the orifice.

The end drops 55 and 56 are loosely secured to the rings 54 and 57 on the rods 20 and 20a and to rings 54a and 57a on the forwardly curved brackets 50 and 52, to permit the ball 62, when driven against them, to drop into apertures 48 and 49 and so out through the underneath channels 63 or 64 in the frame 34.

A putting carpet 65 has a depression 66 therein; the ball 62 being putted into said depression from any angle on the putting carpet.

10 Flags 67 may be inserted in brackets 68 superimposed over the bars 15 to 19 inclusive. Threaded knobs 69 are screwed into the outer ends of the semicircular rods 20 and 20a to retain the rings 54 and 57 and the brackets 21.

15 In use, balls driven from the tee 46 will strike the curtains on the upright frame and fall into the channels in the base, according to the direction and speed of the balls, and will be returned by the channels to the player's position. The harder a ball is driven the farther it will rebound from the curtains; and the direction it is driven will also affect its rebound and also the consequent channel it will drop into.

20 I claim:

1. A golf practice apparatus, comprising a base having a series of arcuate channels therein, and an upright back frame having an arcuate curtain behind the base, from which balls driven against the curtain will fall into the channels selectively according to the direction of the drive, one end of the channels extending to a position adjacent the front edge of the base, whereby the channels will return balls to substantially a player's position in front of the base.

25 30 35 30. 2. An apparatus as set forth in claim 1, the channels and the curtain being curved on substantially a common center.

3. An apparatus as set forth in claim 1, the curtain being inclined backwardly from the top 40 of the frame to the rear edge of the base.

4. An apparatus as set forth in claim 1, the curtain being divided into zones corresponding to the hazards of a golf course, and the channels also corresponding thereto.

45 40 50 45. 5. A golf practice apparatus comprising a back stop, and a base in front of the back stop, made of sheet material pressed to form a series of concentric channels in its upper face and a hollow rim at the outer edge with holes in the top thereof to permit balls to fall into said rim.

GEORGE J. FORCIER.
